UNITED STATES PATENT OFFICE.

GEORGE M. VERITY, OF MIDDLETOWN, OHIO.

PUTTING-GREEN CUP.

1,329,732.

Specification of Letters Patent.

Patented Feb. 3, 1920.

Application filed January 9, 1919. Serial No. 270,290.

To all whom it may concern:

Be it known that I, GEORGE M. VERITY, a citizen of the United States, residing at Middletown, Butler county, Ohio, have invented certain new and useful Improvements in Putting-Green Cups, of which the following is a specification.

This invention, pertaining to improvements in putting-green cups, will be readily understood from the following description taken in connection with the accompanying drawing in which:—

Figure 1 is a plan of my improved putting-green cup;

Fig. 2 a vertical diametrical section taken in the plane of line *a* of Fig. 1.

In the drawing:—

1, indicates a cylindrical metallic casing, open at top and bottom, and adapted to be placed in the turf in the usual manner:

2, a socket for the flagstaff disposed concentrically within the casing and extending from near the bottom of the casing to a point some distance below the top of the casing:

3, vertically disposed radial wings secured to the socket and to the casing and serving to position the socket within the casing and to give stiffness to both these parts:

4, an inturned flange at the lower end of the socket to serve as a rest for the lower end of the flagstaff:

5, an outwardly turned flange at the upper end of the socket, this upper flange serving as a seat for the ball:

6, beveled portions at the upper ends of the wings, the wings extending above the top of the socket and these beveled portions forming inward declines terminating at the ball seat:

7, the flagstaff: and

8, a metallic ferrule arming the lower end of the flagstaff and fitting freely within the socket, and having a rounded lower end.

45 The structure is to be located in the turf as usual. The wings strengthen the socket and the casing and the opening at the lower end of the socket, and the openings between the wings furnish facility for perfect drainage. The inwardly declined portion of the upper end of the wings serves to guide the ball to the ball seat formed by the flange at the upper end of the socket. These declines also serve in guiding the rounded lower end 50 of the flagstaff to the socket. The casing is of such length and the wings give such sta-

bility to the general structure that when the flagstaff is in the socket, the cup is not apt to be displaced by wind pressure upon the flag, nor is the socket itself injured or displaced by carelessness in inserting the flagstaff in the socket. The rounded lower end of the ferrule lessens damage to the turf when the flagstaff is rested upon the ground in position behind the cup to give direction 55 to the player.

I claim:—

1. A putting green cup comprising, a casing, a flagstaff socket disposed concentrically and entirely therein and having its 70 upper end below the top of the casing, and wings disposed vertically in the space between the casing and the socket and extending vertically the length of the socket, said space being open at its top between the 75 wings, combined substantially as set forth.

2. A putting green cup comprising, a casing, a flagstaff socket disposed concentrically and entirely therein and having its upper end below the top of the casing and 80 having its lower end open and provided with an inturned flange, and wings disposed vertically in the space between the casing and the socket and extending vertically the length of the socket, said space being open 85 at its top between the wings, combined substantially as set forth.

3. A putting green cup comprising, a casing, a flagstaff socket disposed concentrically and entirely therein and having its 90 upper end disposed below the top of the casing and provided with an outwardly projecting flange declining toward the socket, and wings disposed vertically in the space 95 between the casing and the socket and extending vertically the length of the socket, said space being open at its top between the wings, combined substantially as set forth.

4. A putting green cup comprising, a casing, a flagstaff socket disposed concentrically and entirely therein and having its upper end below the top of the casing, and wings disposed vertically in the space between the casing and the socket and extending vertically the length of the socket, said 100 space being open at its top between the wings, and the upper ends of the wings being beveled downwardly and inwardly toward the socket, combined substantially as set forth.

5. A putting green cup comprising, a casing, a flagstaff socket disposed concen-

trically and entirely therein and having its upper end below the top of the casing, an outwardly projecting flange disposed upon the upper end of the socket and declining 5 toward the socket, and wings disposed vertically in the space between the casing and the socket and extending vertically the length of the socket, said space being open at

its top between the wings and the wings having their upper ends beveled inwardly and 10 downwardly from the casing to the flange, combined substantially as set forth.

GEORGE M. VERITY.
